WATER CONDITIONER

William M. Cissell, Louisville, Ky.

Application December 30, 1935, Serial No. 56,701

3 Claims. (Cl. 137—101)

My invention relates to apparatus for storing a supply of water and maintaining same at a desired temperature for delivery to the incident boiler or steam generator of the type that is known in the industry as a water conditioner.

The primary object of this invention is to provide an apparatus, which when in service will automatically collect and store hot water condensed from a steam generating and using system, add additional water from a supply source to compensate for the portion which has been used or dissipated, heat and maintain same at a relatively uniform temperature.

Another object is to assemble the apparatus into a self contained unit and thereby dispense with many parts and fittings, together with labor incident to their installation and maintenance, all of which have been accepted as necessary for providing equipment employed to collect and store a water supply at proper temperatures for a steam generator, all without sacrificing the functions of the abandoned elements.

A further object resides in fashioning, proportioning and correlating the constituent parts so as to salvage heat units which are normally dissipated and heretofore regarded as unavoidable losses.

With the foregoing and other objects, which will be revealed as the description of the details of the construction proceeds and hereinafter claimed, it must be understood that variations from the embodiment of my invention, selected for illustration and disclosure, can be indulged without departing from the scope of my invention.

Figure 1 is a cross sectional side elevational view of my water conditioner together with a valve chamber or housing in which is mounted an automatic float controlled valve shown principally in elevation and indicated as being connected to a fresh water source of supply.

Fig. 2 is a modification, on an enlarged scale, of the air duct and the atmospheric vent forming an indispensable part of the apparatus.

Fig. 3 is a further modification of the air vent of Fig. 1 as well as indicating a practical location for same, other than that shown in Figs. 1 and 2. This figure is on a somewhat larger scale drawing.

Structure

Numeral 10 indicates a tank, which is divided into chambers 11 and 12 by means of partition 13 which is indicated as being composed of two disks 131, 132, spaced to provide compartment

133. The "dash-dot" line designated by A, A is to indicate a selected water level for chamber 12, while the level for chamber 11 can widely fluctuate in terms thereof, however, the level of the latter chamber tends to seek the A, A level. Numeral 14 indicates a duct having an elevated opening 141 in chamber 12 and a low opening 142 in chamber 11, and without involving compartment 133. The two chambers are also connected by a duct indicated by numeral 15 which is equipped with valve 152 for the purpose of effecting or maintaining relative pressures between said chambers, in terms of normal atmospheric pressure. Chambers 11, 12 are further connected through duct 103 with opening 102 located above the water line in 12, while opening 101 is placed a few inches above the bottom of compartment which is normally below the water line. This duct functions to convey air or vapor, referred to hereinafter as "gas", from chamber 11 to 12 when the latter is normally full and the water level in the former chamber is sufficiently lowered to expose opening 101. Numeral 16 is a pipe line equipped with a strainer disposed internally of this last mentioned chamber and is connected to a pump, injector, or other device for delivering conditioned water to a boiler or steam generator.

It will be noted that chamber 12 is of materially less capacity than the other chamber and is utilized for receiving cold water from a supply source via pipe line 20 and is under control of an automatic float controlled valve indicated by 21, the full details of which are not illustrated as it forms no part of this invention, however, it can be understood to be the same or substantially the equivalent of the inlet valve embraced by United States Patent No. 1,628,654, which was granted to this applicant.

Valve 21 is connected to housing 22 of compartment 221 by pipe 23. This housing is detachably mounted on tank 10 by means of bolts 24, and is assembled as a unit, i. e., ball float 25 is carried on lever 26 which is pivotally mounted to housing 22 by arm 27 while valve rod 28 abuts the end 29 of lever 26. Baffle or deflector 222 is secured to housing 22 and is provided to direct any surging or spraying of water, as it leaves valve 21, downward toward the bottom of chamber 12. It will be noted from the cross hatching and full lines that the top section is closed and that the lower area is opened, this can be arranged according to judgment, and must provide clearance for lever 26.

In Fig. 2, vent 161 is shown consolidated with 55

air vent 15. There are conditions under which this structure can be used to advantage. Figure 3 shows a section of the partition walls 131, 132, which have been opened to receive duct 151 which is equipped with valve 152. It is to be understood this valve or its equivalent can be organized to be effective for a complete or only a partial stoppage in one direction and open or only a partial stoppage in the other direction. The 10 selection to be exercised according to local conditions and desired objectives.

Operation

This apparatus is constructed and organized 15 to collect condensed steam in the form of hot water, add renewal supply of new water, raise the temperature and store same for use in a steam generator as adverted at the outset, particularly adapted for use in a modern laundry where a material portion of the generated steam 20 is dispensed into the atmosphere.

When this water conditioner, arranged as shown in Fig. 1, is first put into service, valve 21 is open and admits a fresh supply of water 25 through pipes 20 and 23 until chambers 11 and 12 have been filled to a selected level indicated by line A and controlled by float 25. As water enters chamber 12 and then chamber 11 via duct 14, air passes from 12 passing valve 152, to 11 30 via duct 15 (air also similarly passes through duct 103 when the former is first being put into commission) and is forced out of vent 16 into the atmosphere. It must be noted that valve 152 prevents gas from passing into chamber 12 35 which is normally sealed. Hot water for use in the steam generator which serves the system to which this water former is connected is pumped from chamber 11 through outlet 18. As additional or new water is required it will be supplied through valve 21 and its associated members to replace the quantity used or lost. As water is drawn from chamber 11 below the organized level in chamber 12 a small quantity of water will be drawn from the latter which is normally at level A, A, through conduit 14 via mouth 141 and exit 142 thereby tending to establish a balance between the weight of the water and the increasing vacuum chamber 12, since this chamber is now sealed until sufficient water has been drawn from chamber 11 to expose opening 101 50 of duct 103 when gas from chamber 11 will immediately flow therethrough and into chamber 12, thereby relieving the partial vacuum which in turn allows the upper strata of warm water 55 to gravitate through duct 14 and supply the demands of the system as water is pumped through duct 18. When this occurs there is a rapid rush of warm water which is of short duration since water passing from 12 to 11 through 14 will soon 60 close opening 101. As the water level lowers the feed valve 21 admits fresh water, the warm water lodged in the bottom of chamber 12 will be gradually forced upwardly by the incoming cold water, and thereby prepare same to flow 65 from duct 14 when needed in chamber 11. It should be noted that the warmest water is stored above mouth 141 and that it is the first to leave chamber 12. When there is a sudden rush of cold water from valve 21, baffle 222 is provided 70 to subdue same into a gentle flow from compartment 221 along the near vertical wall of compartment 12 onto the bottom of same where it forces the accumulated warmer water to the upper strata, thereby preventing cold water from flowing directly out of the water former via out- 75

let 18. Thus, it will be noted that cold water is not fed into chamber 11 and that provision is made to maintain the latter at a substantial uniform temperature.

As the steam has been used in the system to 5 which the generator is connected, condensed and released, it is returned to chamber 11 via inlet 17. This return is frequently accompanied by a rush occasioned by released steam which results in violent surging within chamber 11. It will 10 be noted that uncondensed steam reaching chamber 11 will be released through vent 16 and that the action resulting from the violent surging is localized by reason of partition 13 which, even when the arrangement shown in Fig. 2 is 15 employed, as only a very small proportion of its area is opened by the duct 14 and vent 15. Thus it will be perceived that float 25 and valve 21 20 are completely and continually protected from said violent disturbance, the result being a greatly increased life for these parts than would be the case if they were exposed to the direct action of the discharged steam and condensed water, and further these parts are kept at relatively low or normal temperatures which is conducive to dependability and constant service. 25

As the temperature of the contents of chamber 11 rises there will be a transfer of heat through partition 13 and the walls of tank 10. The amount of heat transferred can be controlled 30 by consolidating the partition into a unit or spacing the walls 131, 132 of the partition and provide thereby an air chamber 133 which can be vented (not shown) according to local conditions or desired objectives. 35

As a matter of selection or further control of the heat exchange or for any other desired cause the chambers 11 and 12 can be independent integral units connected by the equivalents of ducts 14, 103 and vent 15. And further under some 40 conditions, as when the vapor escaping from vent 16 contains sufficiently high heat units, this vent can be connected to a heat exchanger associated with apparatus for conveying and/or storing the cold water. 45

Although, as adverted at the outset, my invention as disclosed herein is primarily for use as a water conditioner, it is applicable for other purposes. The structure can be modified and substitutions of major or minor parts can be 50 effected to transfer the basic principles to other arts involving an automatic liquid control without departing from the spirit of my invention, therefore I wish to be limited only by the appended claims. 55

I claim:

1. A water conditioner for supplying hot water to a steam generator comprising a tank divided into a hot water chamber and a cold water chamber by a common partition; said cold water chamber having a valved vent, preventing ingress of gas, a source of water supplied thereto under pressure and automatically controlled in response to a water level established therein; said hot water chamber having a vent to atmosphere, 60 an inlet for the return of condensed steam, an outlet for connection to a pump for withdrawing and delivering hot water to said steam generator; said chambers being interconnected by an open water conveying duct extending from 65 a relatively high level in the cold water chamber to a substantially lower level in the hot water chamber; said chambers also being interconnected by an open gas conveying tube extending from the top section of the cold water 70

chamber to the lower section of the hot water chamber carrying gas from the hot water chamber to the other chamber only when the water level of the last said chamber falls below the 5 lower opening of said tube.

2. A water conditioner for supplying hot water to a steam generator comprising a hot water chamber and a cold water chamber disposed at substantially the same level; said cold water 10 chamber having a valved vent and a source of water supplied thereto under pressure and automatically controlled in response to a water level established therein; said hot water chamber having a vent to atmosphere, an inlet for 15 the return of condensed steam, an outlet for connection to a pump for withdrawing and delivering hot water to said steam generator, said chambers being interconnected by an open water conveying duct extending from a relatively high 20 level in the cold water chamber to a substantially lower level in the hot water chamber; said chambers also being interconnected by an open gas conveying tube extending from the top section of the cold water 25 chamber to the lower section of the hot water chamber and carrying gas from the hot water chamber to the other section of the hot water chamber and carrying gas from the hot water chamber to the other

chamber only when the water level of the last said chamber falls below the opening of said tube.

3. A water conditioner for supplying hot water to a steam generator comprising a hot water 5 chamber and a cold water chamber disposed at substantially the same level; said cold water chamber having a valved vent and means receiving and controlling water supplied thereto under pressure; said hot water chamber having a 10 vent to atmosphere, an inlet for the return of condensed steam, an outlet for connection to a pump for withdrawing and delivering hot water to said steam generator, said chambers being interconnected by an open water conveying duct 15 extending from a relatively high level in the cold water chamber to a substantially lower level in the hot water chamber; said chambers also being interconnected by an open gas conveying tube extending from the top section of the cold water 20 chamber to the lower section of the hot water chamber and carrying gas from the hot water chamber to the other chamber only when the water level of the last said chamber falls below the opening of said tube. 25

WILLIAM M. CISSELL.
